SEALING DEVICE

George F. Knowles, Havertown, Pa., assignor to
 Spectrum Manufacturing Company, Philadelphia, Pa., a corporation of Pennsylvania

Application November 22, 1948, Serial No. 61,319

5 Claims. (Cl. 219—47)

1

This invention relates to machines or devices for sealing the edges of envelopes formed of thermoplastic material which is capable of fusion or welding by the application of heat. More particularly, the invention relates to devices for sealing the edges of such envelopes by the application of heat through two jaw-like electrodes between which the envelopes are placed. This method of sealing such envelopes is particularly applicable where the thermoplastic material lends itself to dielectric heating through the application of a high frequency voltage to the two jaw-like electrodes.

Transparent thermoplastic sheets, such as sheets formed of cellulose acetate, have come into use in the formation of sealed protective envelopes for such objects as social security cards and photographs which the owner desires to preserve, particularly when it is desired to carry such objects about and they are subject to wear. Transparent envelopes thus formed are durable and attractive, and they will preserve the enclosed object indefinitely.

The principal object of the present invention is to provide a simple device for sealing such envelopes with a minimum of effort on the part of the operator. The device provided by the invention is especially adapted for the sealing of envelopes about small cards or the like, such as social security cards.

The invention may be fully understood from the following detailed description of a preferred embodiment as shown in the accompanying drawings, wherein

Fig. 1 is a side elevational view of a device constructed according to the present invention;

Fig. 2 is a plan view of the same;

Fig. 3 is an elevational end view of the device taken from the right hand side of Fig. 1;

Fig. 4 is an enlarged sectional view taken along line 4—4 of Fig. 1;

Fig. 5 is an enlarged sectional view taken along line 5—5 of Fig. 2, with the jaws of the device open;

Fig. 6 is a similar sectional view with the jaws closed;

Fig. 7 is an enlarged fragmentary sectional view showing the edge sealing of the envelope; and

Fig. 8 is a perspective view of an envelope-enclosed social security card.

Referring more particularly to the drawings, there is provided a stationary supporting frame designated generally by reference character 10. Mounted on an upright member 11 of said frame is a stationary metal jaw-like electrode 12 which

2

may be secured to said member by means of screws 13. This electrode is generally of rectangular shape, and it has a forwardly projecting flange 14 which extends along the bottom and the two vertical side edges of the electrode, said flange constituting the sealing portion of the electrode, as hereinafter described. Secured to the face of the electrode 12, within the above-mentioned flange, is a resilient cushion member 15 (Fig. 5) which is preferably formed of sponge rubber. An outer facing 16, preferably formed of a plastic material, is provided on the cushion member 15. The cushion member 15 may be secured to electrode 12 by means of suitable adhesive material, and the facing 16 may be similarly secured to the cushion member.

A movable metallic jaw-like electrode 17, similar to the electrode 12 and in opposed relation thereto, is arranged for cooperation with the electrode 12 to perform the sealing function. The electrode 17 also has a projecting flange 18 extending along the bottom and side edges thereof and adapted to cooperate with the flange 14 to effect the sealing action. A resilient cushion member 19 and an associated facing member 20 are mounted on the face of electrode 17, these elements being similar to elements 15 and 16 respectively. The electrode 17 is secured to an insulating plate 21 by means of screws 22 (Fig. 5), and plate 21 is in turn secured to a metal plate 23 by means of bolts 24 (Fig. 2). It will be seen that the electrode 17 is insulated from the supporting plate 23. The plate 23 is secured to a sliding carriage 25 by means of screws 26.

The carriage 25 is slidably supported by the frame 10, and its outer end is pivotally connected at 27 to a link 28, which in turn is pivotally connected at 29 to a lever 30. The upper portion of lever 30 is bifurcated (Fig. 3) and the extending arms 31 thereof are pivotally connected to a bracket 32 by means of a pivot pin 33. The bracket 32 is mounted on the frame 10, above the sliding carriage 25, by means of screws 34.

The lower portion of lever 30 is formed so as to provide a pair of spaced bosses 35 and 36 (Fig. 3) and a third boss 37. The bosses 35 and 36 accommodate rods 38 and 39 (Fig. 2), respectively, which are provided with shoulders against which rest washers 38a and 39a. The bosses 35 and 36 are held against said washers by helical springs 42 and 43 which surround the outer reduced portions of rods 38 and 39. The outer ends of said rods are threaded to accommodate thumb nuts 40 and 41, against which the springs 42 and 43 act. Springs 44 and 45 are arranged on the two

rods between the washers 38a, 39a and the stationary frame 10. The springs normally maintain the operating parts in the positions shown.

The third boss 37 on lever 30 is threaded to receive an adjustable thumb screw 46 which serves as a stop, as hereinafter described. The boss 37 is split and carries an associated bolt 47, by means of which the screw 46 may be held securely in an adjusted position.

The rods 38 and 39 are slidably supported by the stationary frame, and the rods carry collars 48, 49 and 50, 51 (Figs. 1 and 2) which are secured to the rods and move therewith. A shaft 52 extends transversely below the rods 38 and 39 and is rotatably supported by the frame 10. This shaft has keyed thereto a pair of sleeves 53 and 54 which carry extending arms 55 and 56. The ends of said arms extend between the collars 48 and 49 and between the collars 50 and 51 respectively, so that rotary movement of said arms effects sliding movement of the rods 38 and 39. A sleeve or collar 51 is keyed to one end of shaft 52, and carries a crank arm 58, to the outer end of which an actuating rod 59 is pivotally connected at 60. The rod 59 extends downward to a treadle 61 and is pivotally secured thereto at 62. The treadle 61 is pivotally mounted at 63 on a stationary support 64.

The device is adapted to seal three edges of a small envelope, such as shown at 65 in Fig. 8, for enclosing a small flat object such as the social security card 66 shown in the illustration. The envelope is formed of a single sheet which is folded at the top edge 67, the other three edges being sealed by the sealing device. The sealing operation is effected by dielectric heating, and to this end a high frequency voltage is applied between the metal electrodes 12 and 17. The stationary electrode 12 is electrically connected to the metal frame 10 by virtue of its attachment thereto, and an insulated conductor 68 (see Fig. 1) is connected to the frame and extends to one terminal of a suitable voltage supply source (not shown). The latter may be a conventional high frequency voltage generator and requires no illustration. A coaxial tuner 69 may be connected to the other terminal of said source. The coaxial tuner is stationary and is provided with a contact finger 70 which is in wiping engagement with the movable electrode 17.

The high frequency voltage generator is normally maintained in inoperative condition by a micro-switch 71 biased to open position. The micro-switch is supported by a bracket 72 mounted on an upright member 73 of the frame 10. A collar 74 on rod 38 engages the micro-switch arm 75 to close the switch at a certain point in the operating cycle, as hereinafter described.

Normally the two electrodes are open as shown in Fig. 5, forming a slot-like space in which the folded envelope member and the associated card may be placed. An important feature of the invention is the arrangement for supporting the envelope member and the associated card, as now to be described. A pair of rotatable arms 76 and 77 (Fig. 4) are rotatably supported on rod 38 and are urged into engagement with the electrodes by a spring 78. These arms have flat finger portions 79 and 80 which normally span the open electrodes. The arms are prevented from moving longitudinally on rod 38 by a pair of collars 81 and 82 (Fig. 1). Similarly, a pair of arms 83 and 84 (Fig. 4), having finger portions 85 and 86, are rotatably supported on rod 38 and are urged into engagement with the elec-

trodes by a spring 87. Collars 88 and 89 (Fig. 5) serve to prevent the latter arms from moving longitudinally on rod 39. By virtue of this supporting arrangement, it is necessary merely to drop the folded envelope member and the associated card into the space between the electrodes as shown in Fig. 5. When the electrodes are open as shown in Fig. 5, the envelope-supporting elements span the electrodes but at that time the switch 71 is open so that there is no voltage applied across the electrodes and no short circuiting action through the envelope-supporting elements.

When the device is actuated by depressing the treadle 61, the movable electrode 17 is moved to closed position, as shown in Fig. 6, and the resilient elements carried by the electrodes grip the envelope member firmly while leaving free the three edges to be sealed. At the same time, the above-described supporting elements are moved out of engagement with the electrode 17, as may be seen in Fig. 6. However, the envelope member is gripped by the resilient elements on the electrodes before the supporting elements are moved to non-supporting position. The switch 71 is closed after the supporting fingers 79, 80, 85, 86 have been moved out of engagement with the electrode 17. This operating sequence is necessary in order that the said fingers will not form a short circuit between the electrodes.

When the treadle 61 is released, the reverse sequence takes place. First the switch 71 opens, then the supporting fingers 79, 80, 85, 86 move to supporting position, and finally the jaw-like electrodes release the envelope.

The detailed operation of the device to give the desired operating sequence may be understood by considering Figs. 1 and 2. As the treadle 61 is depressed, the springs 42, 43 cause lever 30 to move as though the latter were rigidly connected to rods 38, 39. As the rods 38, 39 and the lever 30 move toward the left the springs 44, 45 are compressed. When electrode 17 reaches the closed position, lever 30 is stopped but the rods 38, 39 are able to continue their movement against the resilience of springs 42, 43. During the continued movement of rods 38, 39, the envelope-supporting fingers move out of engagement with electrode 17 and then the switch 71 is closed.

When the treadle is released, the springs 42, 43 move the rods 38, 39 toward the right, causing the switch 71 to open and moving the envelope-supporting fingers to supporting position. Meanwhile the springs 44, 45 urge lever 30 toward the right and finally cause the electrode 17 to release the envelope.

It will be apparent that the device is designed to give the above-described operating sequence. To this end springs 42, 43 are somewhat heavier or stiffer than springs 44, 45.

When the movable electrode 17 moves to closed position as above described, the flanges 14 and 18 of the two electrodes exert pressure on the edges of the envelope member to be sealed. When the high frequency voltage is applied, the said edges are subjected to simultaneous pressure and heat, the heating of the thermoplastic material being effected dielectrically as will be well understood. As a result of the heat and pressure, the edges are fused or sealed as shown at 90 in Fig. 7. This requires only a few seconds during which the operator holds the treadle 61 in depressed position. During the sealing operation, there is a tendency toward slight enlargement of the envelope as the softened thermoplastic material flows slightly

outward under the exerted pressure. However, the construction of the envelope-supporting elements, as shown in Fig. 4, permit the fingers 19, 20, 85, 86 to return even though the edges of the envelope may be extended by the sealing operation.

Mention was made previously of the adjustable stop screw 46. This stop element does not normally become effective, but in the event that the device is actuated without placing an envelope member and associated card between the electrodes, the end of screw 46 engages the adjacent portion of the frame 10 and prevents sufficient movement of electrode 17 to cause engagement of the electrode flanges 14 and 18. This prevents short circuiting of the high frequency source which would otherwise be caused by direct engagement of the electrodes.

Normally, the operating mechanism will be housed within a casing, a portion of which is shown at 91. Such casing may be provided with a slot opening 92 into which a folded envelope member and an associated card may be dropped.

It will be apparent from the foregoing description that the device provided by the invention is simple in construction and operation and is easy to operate. The operator simply drops a folded envelope member and associated card into the slot opening, depresses the treadle 61 for a few seconds, and then removes the sealed envelope. Thus it is possible for a single operator to seal envelopes at a rapid rate.

While a preferred embodiment of the device has been illustrated and described, it will be apparent that the invention is not limited to the structural details thereof since it is obvious that the various modifications could be made without departing from the essential structure and mode of operation.

I claim:

1. In a device for sealing the edges of envelopes formed of thermoplastic material, a stationary vertical electrode, a movable vertical electrode arranged in cooperative relation with said stationary electrode, metallic means normally engaging said electrodes for supporting an envelope between said electrodes when the latter are open, a normally-open switch adapted to control application of a voltage to said electrodes, a manually-operable member, and means operable by said member to actuate said movable electrode to closed position, to move said envelope supporting means out of engagement with said movable electrode, and to close said switch, in the recited sequence.

2. In a device for sealing the edges of envelopes formed of thermoplastic material, a stationary vertical electrode, a movable vertical electrode arranged in cooperative relation with said stationary electrode, metallic means comprising spring-biased fingers normally engaging said electrodes for supporting an envelope between said electrodes when the latter are open, a normally-open switch adapted to control application of a voltage to said electrodes, a manually-operable member, and means operable by said

member to actuate said movable electrode to closed position, to move said envelope supporting means out of engagement with said movable electrode, and to close said switch, in the recited sequence.

3. In a device for sealing the edges of envelopes formed of thermoplastic material, a supporting frame, a stationary jaw-like electrode mounted on said frame, a movable jaw-like electrode arranged in cooperative association with said stationary electrode, movable carriage means for said movable electrode supported by said frame, metallic means normally engaging said electrodes for supporting an envelope between said electrodes when the latter are open, and means for moving said carriage means to effect closure of said electrodes, and for moving said envelope-supporting means out of engagement with one electrode.

4. In a device for sealing the edges of envelopes formed of thermoplastic material, a supporting frame, a stationary jaw-like electrode mounted on said frame, a movable jaw-like electrode arranged in cooperative association with said stationary electrode, movable carriage means for said movable electrode supported by said frame, metallic means normally engaging said electrodes for supporting an envelope between said electrodes when the latter are open, a normally-open switch carried by said frame and adapted to control application of a voltage to said electrodes, a manually-operable member, means operable by said member to move said carriage means to effect closure of said electrodes, other means operable by said member to move said envelope-supporting means out of engagement with one electrode, and still other means operable by said member to effect closure of said switch.

5. In a device of the character described, a pair of relatively movable electrodes arranged to receive therebetween an object for treatment by said electrodes, metallic means normally engaging said electrodes for supporting said object between said electrodes when the latter are open, a normally-open switch adapted to control application of a voltage to said electrodes, a manually-operable member, and means operable by said member to effect closure of said electrodes, to move said supporting means out of engagement with one of said electrodes, and to close said switch, in the recited sequence.

GEORGE F. KNOWLES.
